UNITED STATES PATENT OFFICE.

FRANK R. STEHM, OF DES MOINES, IOWA, ASSIGNOR TO ENAMEL CONCRETE COMPANY,
OF DES MOINES, IOWA, A CORPORATION OF SOUTH DAKOTA.

CONCRETE-FORMING MACHINE.

1,173,987.

Specification of Letters Patent. Patented Feb. 29, 1916.

Application filed August 22, 1907. Serial No. 389,706.

To all whom it may concern:

Be it known that I, FRANK R. STEHM, a citizen of the United States, residing at Des Moines, in the county of Polk and State of Iowa, have invented a certain new and useful Concrete-Forming Machine, of which the following is a specification.

The objects of my invention are to provide a machine for automatically constructing concrete and other articles of various kinds, into which the materials which are used to form the article to be constructed are delivered, and from which the completed article is delivered, without manual assistance.

A further object is to provide a machine by which the materials are thoroughly mixed in the proper proportions, are fed properly into the various molds, are packed into a dense and solid form within the molds, and the body of the molds released from the articles to allow the bottom of the molds or pallet to be removed and set away with the hardened articles upon it.

A further object is to provide a machine of this class by which articles of various size, shape and dimension may be automatically constructed, which may have a smooth, glossy, or polished surface or surfaces when they have dried.

A further object is to provide a machine by which surfacing material may be fed into the mold of any desirable constituency, and a coarser material may be deposited upon said surfacing in the desired proportions and of the desired mixture, and a mechanism for applying pressure to the material while within the molds, to densify and form these articles, and to provide a mechanism for releasing and delivering the articles thus constructed at the rear end of the machine where they can be easily taken away, and stored for drying.

A further object is to provide a machine which is so constructed, arranged and timed as to accomplish all of these results in forming the articles as they are advanced through the machine by means of the conveyer, and to accomplish all of the results step by step, applying one of the machine steps to one set of articles at the same time, certain other steps are being applied to the other articles.

My invention consists in certain details in the construction, arrangement and com-

bination of the various parts of the device, whereby the objects contemplated are attained, as hereinafter more fully set forth, pointed out in my claims and illustrated in the accompanying drawings, in which—

Figure 1 shows, in elevation, the right side of my machine, with the aggregate mixer and water pipes removed. Fig. 2 is an elevation of the left side of my machine with the conveyer removed. Fig. 3 is a detail elevation of the rear side of the edge surfacing feeder for preparing and delivering the surfacing material to the mold. A portion of the side of this is broken away to show the interior construction. Fig. 4 is a longitudinal, sectional view of one of the mold frames, showing its molds or compartments and the mechanism for supporting the releasing bottom or pallet. Fig. 5 is a vertical, sectional view of the edge surfacing feeder, cut on the line 5—5 of Fig. 3. Fig. 6 is an elevation of the left end of the end surfacing feeder. Fig. 7 is a vertical, sectional view of the end surfacing feeder, showing the interior construction thereof, illustrating the mechanism for delivering the surfacing into the end of the mold in the act of delivery. Fig. 8 is a detail end view of the cam and counterbalancing weight, which together operate and release the mechanism for delivering the surfacing into the ends of the molds. Fig. 9 is a detail view, showing a portion of the plate which delivers the surfacing into the ends of the mold. Fig. 10 is a detail view, showing the front side of one of the mold frames and the mechanism for making spaces at the end of each mold into which the surfacing is poured for the ends of the article which are being formed. Fig. 11 is a sectional view of the machine for making spaces at the end of the mold, cut on the line 10—10 of Fig. 10. Fig. 12 is a vertical, sectional view of the mechanism for making spaces at the ends of the article in the molds, cut on the line 11—11 of Fig. 10. Fig. 13 is a detail, plan view of the gears for operating the article releasing mechanism. Fig. 14 is a detail view, showing in elevation and section the tamping plunger and the mechanism by which it is operated for applying pressure to the articles within the molds. Fig. 15 is a detail, sectional view of the rear end of the device, cut on the line 14—14 of Fig. 16, showing the brick releasing plunger.

and the mechanisms which it controls, and by which it is operated, and also in detail the conveyer and the pallet delivering mechanism. Fig. 16 is a rear elevation of the machine with a portion broken away to show in detail certain portions of the interior mechanism. Fig. 17 is a cross sectional view of the aggregate hopper which forms the body of the article to be constructed. Fig. 18 is a detail view of one end of the mechanism for supporting the mold frame after the articles have been released from the molds. Fig. 19 shows, in elevation, the right side of two of the gears for operating the releasing plunger and timing its operation. Fig. 20 shows, in elevation, the left side of the gears shown in Fig. 19. Fig. 21 is a perspective view of one of the pallets which form, and is, in operation, the detachable bottom of the mold. Fig. 22, is a detail view of the dog for driving the main conveyer and the mechanism for releasing the dog. Fig. 23 is a perspective view of the pallet inverted, and Fig. 24 shows, in perspective, one of the sections of the conveyer, which I have called, for the sake of convenience, the pallet bed plate, upon which the pallet or detachable bottom of the mold rests when in the machine.

The frame.—The entire operative parts of this machine are mounted on a frame comprising two sides 25 and 26, suitably braced relative to each other by transverse members. Extending longitudinally of the lower inner portion of the sides 25 and 26 are the rails 27 and 28, and mounted some distance above the top of each side of the frame and above the sides 25 and 26 are the rails 29 and 30. These rails are constructed and arranged to support the conveyer, to be hereinafter described, as it is operated.

The conveyer.—Mounted at the ends of the frame and extending transversely of it are two shafts 31 and 32. On the shaft 31 and near its ends are two sprockets 33. Mounted on the shaft 32, and near its ends are two sprockets 34. I have provided an endless conveyer, comprising a series of pallet bed plates 35, which are connected with each other by means of two sprocket chains 36 and 37, which pass over the sprockets 33 and 34, and are mounted upon the rollers 38, which roll over and are supported by the rails 27 and 29 in operation.

Molds.—Detachably connected with each end of each of the pallet bed plates and extending upwardly therefrom, is a retaining post 39, which is screw threaded at its lower ends and tapered slightly immediately inside of the screw threaded portion, so that when they are screwed into the pallet bed plates, they are braced against lateral or longitudinal strain and are held in alignment with each other. Secured between the pair of posts on each of the pallet bed plates

is a mold frame comprising two sides 40 and two end portions 41. Extending transversely of this mold frame is a series of cross pieces 42, which, together with the ends and sides, form a series of molds into which the substances, for forming the article to be constructed by the machine, are poured. The bottom of this series of molds is formed, preferably by a pallet 43 resting upon the pallet bed plate, and is retained therein by the projections 44 on the bed plate which enter notches 45 in the pallet board, and the upper surface of which engages the lower portion of the mold frame. The upper portion of this pallet bed plate is finished either with a smooth, non-adhesive or polished surface, so that when the article which has been formed within the mold, in engagement with the upper surface of this pallet has been removed from the mold and is set away to dry, without breaking the contact between the article formed by the mold and the surface of the pallet, a finished surface similar to that of the surface of the pallet is imparted to the article.

At each end of the mold frame I have provided two retaining lugs 46 having openings 47 extending through them which receive the posts 39, so that the mold frames 95 may be moved on said posts for the purpose of allowing the article to be held in unbroken contact with the pallets as this mold frame is elevated and drawn out of contact with the articles formed by the molds in 100 this mold frame. These posts 39 are cut away slightly on one side to form a projection 48 for limiting the outer movement of the mold frames and prevent their slipping off the posts after having been delivered of the articles formed within them.

Rear mold supporting tracks.—In each end of each of the side plates 40 of the mold frame I have provided a notch 49 designed to receive the rear auxiliary tracks, of which there are two in number, one on each side of the frame, some distance above and largely at the rear of the tracks 29. Each of these rear tracks comprises a spring pressed member 50, and a rearwardly and downwardly extending curved portion 51. The spring pressed members 50 are secured to the inner end of the shanks 52, which extend outwardly through a supporting bar 53, and a collar 54 is provided on each of the shanks 52, and a spring 55 is mounted between the collars 54 and the supporting bars 53 for yieldingly holding the spring pressed member 50 at its outer limit of movement. Each of the spring pressed members 50 are tapered, with their narrow edges lowermost and the upper corners of each side plate of the mold frame is inclined inwardly to allow the mold plate to act against the spring pressed members of the 130

rear auxiliary tracks and force said members outwardly until they come to a point directly in line with the notches 49, whereupon the spring pressed members are forced into said notches and the mold frames maintained at their upper limits of movement until they are advanced rearwardly by the action of the conveyer and drawn over the curved portion of the rear auxiliary track. It is while the mold frames are thus maintained in an elevated position relative to the rest of the conveyer that the pallets and the articles remaining thereon, after the molds have been elevated, are removed from the machine and set away to dry and harden.

The front mold supporting tracks.—Connected with the forward ends of each side of the main frame is a curved track 55, so arranged that the upper surfaces of these tracks will engage the under surfaces of the molds while they are at their outer limits of movement, and will retain them some distance above the pallet bed plates until the mold has passed inside of a vertical line, drawn through the forward end of the frame to enable the placing in position of the pallets on the pallet bed plates, after which the mold frames drop by their own weight and are forced downwardly by the curved guides 55^a into engagement with the pallet, which completes the molds and makes them in readiness for receiving the material for forming the article or articles to be produced.

The conveyer driving mechanism.—Mounted on the right end of the shaft 32 is a ratchet 56, and loosely mounted on said shaft 32, and on each side of the ratchet 56 are the pawl bearing members 57, having the pawl 58 pivotally mounted between them to engage and drive the ratchet, and with it the conveyer, as the pawl bearing member 57 is operated. Mounted on the opposite side of the ratchet 56 from the pawl 58 is a spring maintained dog 59 which retains the ratchet 56 against movement while the pawl 58 is acting, on the return stroke of the pawl bearing member 57, thus retaining the conveyer and its parts in the proper position for carrying out the operations contemplated. It is very essential that these parts be arranged and maintained at their proper positions accurately, owing to the fact that the large number of operations to be accomplished by the machine necessitate accurate adjustment being maintained at all times, as will be seen more fully hereinafter.

Extending upwardly from each of the sides 25 and 26 of the main frame are two uprights 60 and 61, which are properly reinforced for supporting and sustaining a great amount of weight and pressure upon them. These uprights 60 and 61 are connected at their upper ends by suitable arches 62 for maintaining them in the proper po-

sition relative to each other. There are a number of suitable cross braces connecting these uprights at their lower ends, and also a number of other uprights to properly maintain the sides of the main frame in position relative to each other. There are two uprights 63 and 64 extending upwardly from the extreme rear ends of each side of the main frame which are suitably connected by an arch or arches 65.

Extending longitudinally of the frame and rotatably mounted in suitable bearings secured to the uprights 61 and 64 is a main driving shaft 66 of the machine, upon which is mounted the ordinary drive pulley 67, and the idler 68, so arranged relative to each other that the belt may be readily shifted from one to the other at the pleasure of the operator.

Mounted on the driving shaft is a gear 69, a large balance wheel 70 and a bevel gear 71, for the purposes of transmitting power to the operative parts of my device and maintaining the speed uniform. Extending across the rear of the machine and mounted in suitable bearings is a shaft 72 having a bevel gear 73 on its left end in mesh with the bevel gear 71 on the main driving shaft 66, and also having a small gear 74 on its right end. Mounted on the shaft 75, which is beneath the shaft 72, is a gear 76 in mesh with the gear 74. Attached to one side of the gear 76 at one end, and at its other end to the pawl bearing member 57, is an adjustable pitman 77, so arranged that as the gear 76 is rotated, the pawl bearing member will be oscillated to operate the pawl 58 and drive the endless conveyer of the machine, an adjustment of the pitman 77, provides for alining the mold frames with the plungers hereinafter described.

Extending transversely of the machine and mounted on the brackets projecting forwardly from the uprights 63 and 64, is a shaft having mounted on its right end the large gear 79 which is in mesh with the small gear 74. This shaft has mounted on it a cam 80 which operates the ejector plunger, hereinafter described. The shaft 78 also has mounted on it the mutilated gear 81, which operates the mechanism for raising the mold frame, while the releasing plunger holds the article formed by the mold, in contact with the pallet, as is set out more fully hereinafter.

As explained above the oscillation of the pawl gear 57 operates the ratchet wheel 56. The operating pawl 58 is, however, pivotally mounted upon the stud 58' carried by the pawl gear 57, and is provided with an extension 82 having thereupon a pin 83. The bent lever 84 pivotally mounted upon one of the uprights 63 may be depressed by means of the link 85 which is attached at one end to the bent lever 84 and to the other to a

5 pivot pin eccentrically mounted on the large gear 79. It will be obvious that by this arrangement the link 85 will be periodically depressed and through the bent lever 84 will rock the pawl 58 when the pawl gear 57 is moved upwardly to interrupt the driving engagement between the pawl and the ratchet 56, and thus cause a dwell in the conveyer.

10 By the operating mechanism above described, the conveyer is intermittently operated at the desired rate of speed, to enable the pallets to be placed upon the pallet bed plates at the one end, and removed 15 therefrom, together with the completed article, at the other, and also allow for the operation of the rest of mechanisms between the intermittent steps of the advancement of the conveyer.

20 *Edge surfacing feeder.*—At the forward end of the machine frame, and extending upwardly from the sides, are the uprights 86, upon which the feeder is mounted, for delivering the surfacing material to the 25 molds, and for supplying the proper quantities of material and mixing these materials together before delivering them. The feeder referred to comprises a mixing trough 87, open at the top. Extending longitudinally 30 of the trough and mounted in its end portions is a shaft 88, having a series of mixing blades 89 on it spaced some distance apart for thoroughly mixing the materials delivered into it, both before and after water 35 has been supplied as the shaft is rotated. Secured to the mixing trough 87, and mounted above its right end is a material storing and delivering hopper which is divided into two compartments by means of 40 a partition 90, and two deflectors 91 and 92. Extending longitudinally of the hopper 90, and on either side of the partition are two shafts 93 and 94.

45 Mounted on the shaft 93 is a feeding wheel 95, and on the shaft 94 a feeding wheel 96. These wheels 95 and 96 comprise a hub and a series of radial blades which serve to retain the materials within the hopper while stationary, and advance this material to a delivering point beneath them as they are operated. By regulating the relative speeds of these feeding wheels, the operator can feed the proper quantities of materials into the mixing trough.

55 The shafts 93 and 94 are properly geared together at their left ends by means of two gears 97. Immediately beneath the left end of the mixing trough 87 is a grooved feeding shaft 98 mounted on shaft 107, having 60 two or more grooves 99 therein, into which the material falls after it has been thoroughly mixed by the mixing blades 89, which cause the material to be forced to the delivery or left end of the mixing trough, beneath which the feeding shaft is mounted.

This construction allows the material to be thoroughly mixed as it is advanced to the feeding shaft, from which it is delivered through the opening 100 onto a feeding plate 101. This feeding plate is secured to the 70 rotatable shaft 102, which extends to the right end of the machine, in such a way, that as the feeding plate is released, the mixed surfacing material will slide over it into the various molds which stand in readiness beneath this feeding plate. Extending 75 from the outer edge of the upper surface of the feeding plate 101 inwardly, is a series of ribs 103, so arranged as to direct the mixture into the various molds within the mold 80 frame, in substantially equal amounts, to suitably fill the molds at each delivery of the feeding plate. Mounted on the right end of the shaft 102 is a rock arm 104 which has the weight 105 at one end and a roller 106 at its 85 other end.

Extending transversely of the machine and beneath mixing trough 87 is a shaft 107. Mounted at the right end of this shaft 107 is a bevel gear 108, and at the left end of 90 said shaft is mounted a crank wheel 109. Mounted on the shaft 107, immediately inside of the crank wheel 109 is a cam 110, designed to coact with the roller 106 to maintain the feeding plate 101 in a closed position for retaining the material within the 95 grooves 99 of the grooved feeding shaft 98 mounted on shaft 107. As soon as the cam releases this shaft, the weight 105 becomes effective and rotates the shaft slightly to 100 throw the feeding plate into an open position, and allows the surfacing material to slide over it into the molds, as shown in Fig. 5 of the drawings. This feeding operation is regulated properly by the rotation of the 105 shaft 107. Secured to the right end of the shaft 94 is a ratchet 111. Pivotaly mounted on the shaft 94 and outside of the ratchet 111 is a bell crank lever, comprising the 110 pawl bearing arm 112 and the slotted arm 113. Pivotaly attached to the pawl bearing arm 112 is a pawl 114, designed to engage the teeth of the ratchet 111, and actuate it, to drive the shafts 94 and 93 as the bell crank lever is operated by means of a pitman 115, which is adjustably secured to the slotted arm 113 of the bell crank lever and to the crank wheel 109.

115 It will be seen that as the feeding shaft 107 is operated, the feeding wheels mounted 120 on the shafts 93 and 94 will be driven to deliver the material within them in proper proportions into the mixing trough, and the material when mixed will be delivered by the grooved feeding shaft 98, which is secured to the shaft 107 onto the feeding plate 101, and over it into the molds in the mold frames on the conveyer beneath.

125 By means of the slot in the slotted arm 113, and the pawl in the upper end of the 130

pitman 115, the stroke of the rock arm can be regulated to increase or diminish the quantity of material being fed into the mixing trough beneath the material storing and delivering hopper 90.

5 The bevel gear 108, through which the feeding plate 101, the grooves feeding shaft 98, and the feeding wheels mounted on the shafts 93 and 94 are operated, is driven by means of a bevel gear 116, loosely mounted on the shaft 117, which shaft is rotatably mounted on the left side of the machine, in substantially the same plane as the shaft 107 is mounted. Keyed to the front end of the 10 shaft 117 is a clutch 118, designed to engage a lug 119 on the bevel gear 116 for throwing said gear into operative relation with the shaft 117 for driving the shaft 107. This clutch 118 is thrown into and out of engagement with the lug 119 on the bevel gear 116 by means of a lever 120 which is pivoted to it and to a support 121 secured to the left upright 86, so that by means of this lever, the gear 116 is thrown into or out of gear 15 20 with the gear 108. Near the rear end of the shaft 117 I have mounted a gear 122. In mesh with this gear 122 is a gear 123 which is secured to a shaft 124 that extends forwardly from and is substantially in a line 25 parallel with the shaft 117.

30 Mounted on the shaft 124 in front of the drive wheel 67 is the gear 125, through which this shaft 124 is operated, and through which the tamping plunger, to be hereinafter described, is also partially operated.

35 Mounted on the shaft 126, which is immediately above the central portion of the tamping plunger, above referred to, and extending longitudinally of a portion of the 40 machine, is a gear 127 in mesh with the gear 125. This gear 127 in turn is in mesh with a small gear 128 which is mounted on a short shaft 129 substantially parallel with the shaft 126, and which has mounted at its rear 45 end a gear 130 which is in mesh with the gear 69 on the main driving shaft, so that the feeding plate 101, the grooved feeding shaft 98 and the feeding wheels mounted on the shafts 93 and 94 are driven through the 50 mechanism, above described, by the main driving shaft 66 of the machine.

55 The shaft 88, and with it the mixing blades 89, is driven by means of a bevel gear 132 which is in mesh with the bevel gear 133 on the auxiliary driving shaft 134, which is mounted on the right side of the machine, substantially in line with the shaft 88. This auxiliary driving shaft has mounted on it the driving wheel 135 and the idler 136, so 60 arranged relative to each other that the belt by which the power is transmitted to the driving wheel 135 may be easily shifted from one to the other to throw the auxiliary driving shaft out of or into operation readily. Suitable pipes 137 lead from a

source of supply into the material storing and delivering hopper 90, designed to keep this hopper suitably filled with the various materials used for surfacing the article to be constructed.

70 *The aggregate hopper.*—A slight distance at the rear of the edge surfacing feeder, and suitably mounted on the uprights 138, which form a part of the frame, is an aggregate hopper 139, into which the body or aggregate material is fed by a suitable mixing machine 140, and from which this aggregate material is delivered into the molds on top of the surfacing material which has already been delivered into these molds by the edge 75 surfacing feeder. This hopper comprises two sides 141 and two end portions 142, and is adjustably mounted relative to the uprights 138 by means of lugs 143 extending outwardly from the ends of this hopper, and set screws 144 extending through this lug into the upper portions of the uprights 138. This adjustment of the aggregate hopper enables the operator to keep the lower edges of this hopper in their proper relation 80 to the tops of the molds, so that as the conveyor and molds are advanced, these molds are left suitably filled with the material.

85 *The facing spacer.*—Mounted on the main frame is a facing spacer supported by two 90 uprights 145 on each side of the machine and at the rear of the aggregate hopper 139. Connected to the uprights 145, and rotatably mounted at the top portion is a crank shaft 146, having two cranks 147 and 148 therein. 95 On the left end of the crank shaft is a bevel gear 149, adjustably mounted by means of the set screw 150, the bevel gear 149 is in mesh with the bevel gear 151, on the shaft 124, so that as the main driving shaft 66 is 100 operated, and when the bevel gears 147 and 149 are in mesh with each other, the crank shaft 146 will be operated.

105 I have provided a set screw 152 which passes through the bearing which supports 110 the left end of the shaft 146, so arranged that when the bevel gear 149 is held out of engagement with the bevel gear 151, the crank shaft can be locked in position by means of this set screw to hold the cranks 115 147 and 148 at their upper limit of movement for holding the operative parts of the facing spacer out of the path of movement of the mold plates. This is done to enable the machine to be operated without the use 120 of the facing spacer, if desired.

125 Slidingly mounted in the inner surfaces of the uprights 145 are two slides 153 and 154 which are connected with each other by means of a blade supporting bar 155, having a series of spacing blades 156 mounted thereon, and so arranged relative to the bar that as the bar is moved downwardly and the molds are in the proper position beneath them, these spacing blades will enter the end 130

of the mold and crowd the material, which is within it, sufficiently to admit the blades and leave said material away from the end of the mold, when the blades are withdrawn 5 so that the end surfacing material may be poured into the opening or spaces thus formed, by the crowding of the material within the molds.

Pivottally attached to the slides 153 and 10 154 at one end, and at their other ends to the cranks 147 and 148, respectively, are the pitmen 157 and 158, so arranged that as the crank shaft 146 is rotated, the blade supporting bar 155 and the blades 156 will be reciprocated vertically to accomplish the result desired.

The end surfacing feeder.—At the rear of the facing spacer, and mounted on two uprights 159 is an end surfacing feeder, constructed similar to the edge surfacing facer with a mixing trough 160, having a shaft 161 extending longitudinally of it, on which there are mixing blades 162. There is a material storing and delivering hopper 163 20 at the right end of this mixing trough in which there are two feeding wheels 164 and 165, shown in Fig. 7. Beneath the left end of the mixing trough 162 is a grooved feeding shaft 166, having two or more grooves 167 therein. There is an opening 168 beneath the grooved feeding shaft, through which the material passes and is delivered onto a feeding plate 169 which is secured to the shaft 170. This feeding plate has a series 30 of ribs 171 on its upper surface which guides the material as it passes over it, into the spaces formed by the facing spacer at one end of each mold, into which the facing material is to be delivered, as shown clearly 40 in Fig. 7. The grooved feeding shaft 166 is mounted on a shaft 172 which extends across the machine, and has mounted at its left end a bevel gear 173, in mesh with the bevel gear 174 that is loosely mounted on the shaft 117, which, as above stated, is driven from 45 the main driving shaft 66. I have provided a lug 175 on the bevel gear 174 designed to be engaged by a clutch 176, controlled by a lever 177, pivoted to a support 178 secured 50 to the left upright 159. By throwing the clutch into engagement with the lug 175, the shaft 117 operates the bevel gear 174 to drive the shaft 172, and with it a crank wheel 179 that is rigidly secured to the left 55 end of this shaft 172. Attached to the shaft 172 inside of the crank wheel 179 is a cam 180 designed to operate a bell crank lever 181 attached to the feeding plate shaft 170. The cam is designed to hold the feeding 60 plate 169 in a closed position until the proper time to have it released to deliver the material, when it is drawn open by a weight 182 secured to the bell crank lever 181, as shown in Fig. 8 of the drawings.

65 Mounted on the end of the shaft support-

ing the feeding wheel 164 is a ratchet 183 operated by a bell crank lever, having a pawl bearing arm 184 thereon, and the slotted arm 185. The pawl bearing arm 184 bears the pawl 186, which engages the 70 ratchet and rotates as the bell crank lever is operated, by means of the pitman 187, connecting the slotted arm 185 with the crank wheel 179. The slot in the slotted arm 185, together with the pawl in the upper end 75 of the pitman, affords an adjustment by which the delivery of material from the material retaining and delivering hopper, into the mixing trough beneath, is regulated.

From the above description, it will be seen 80 that the feeding plate 169, the feeding shaft 166, and the feeding wheels 164 and 165 are operated from the main driving shaft 66. There are two supply pipes 187 for feeding the material from general storage into the 85 compartments of the material storing and delivering hopper, which compartments are formed by a partition 188. There are also two guide plates 189, partially beneath the feeding wheels 165 and 166 similar to the 90 feeding plates in the hopper 90. Secured to the right end of the shaft 161 is a bevel gear 190 in mesh with the gear 191, which latter gear is rotatably mounted on the auxiliary driving shaft 134. I have provided a clutch 95 mechanism 192 for throwing the gear 191 into and out of operative relation with the auxiliary driving shaft 134, so as to throw the end surfacing feeder out of gear when it is desirable not to put an end surfacing on 100 the article which is being constructed; that is, the spacer and the end surfacing feeder are, under these circumstances, both kept out of gear when the article which is being made requires no end surfacing.

The tamping plunger.—Mounted in the upright 60 is a crank shaft 195, having the gear 196 at one end thereof in mesh with the gear 127, above referred to. Near the rear end of the shaft 124, upon which the 110 gear 125 is mounted I have provided a crank 197 which is between the sides of the upright 61, and is opposite the crank in the crank shaft 195. Mounted between the uprights 60 and 61, immediately above the 115 molds of the conveyer and capable of vertical movement, is a plunger head 198. Pivottally attached to one end of the plunger head 198 and to the corresponding end of the cross brace 62 is a toggle 199 which is 120 pivoted together at its central point by the pin 200. Pivottally attached to this pin 200 and adjustably connected with a bearing 201, which is mounted on the crank of the crank shaft 195 is a pitman 202. Pivottally 125 connected with the opposite ends of the plunger and the cross brace 62, from that to which the toggle 199 is attached, is a toggle 203, the inner ends of which are pivoted together by means of the pin 204. This pin 130

is connected with a pitman bearing 205, which is mounted on the crank 197 by means of an adjustable pitman 206. By the arrangement of gearing and construction of the tamping plunger, the plunger head will be raised and lowered as the main driving shaft 66 is operated, and on account of the construction and arrangement of gearing, a great amount of pressure is exerted as the plunger is moved downwardly, so that when the tamper members 207, which form a portion of the plunger head 198, enter the individual molds on the conveyer beneath them, the material in the molds will be forced toward the sides and lower surface of the mold and into a dense and compact mass. This tamping plunger is so constructed and arranged as to operate at certain predetermined intervals to tamp the material in each set of molds as the mold frame on the conveyer passes beneath it.

I have provided a heavy reinforcing cross bar 208 which connects the sides of the main frame immediately beneath the conveyer, which serves to support the conveyer and maintain it against the severe pressure which is brought to bear upon it by means of the plunger head being forced against the material in the molds upon the conveyer.

Attached to the lower ends of the guides 209 and 210, in which the plunger head is slidably mounted, are two bars 211 and 212, under which each mold frame stands while the tamping plunger is being operated, which serve to retain each of these molds at its lower limit of movement, and prevents the mold from being raised on the return stroke of the plunger head.

It has been found that the conveyer will bring the molds in line with the tamping members of the plunger, but if it is desired to bring these more accurately in line, a mechanism for accomplishing this result can be easily attached to the machine adjacent to the plunger supports.

The mold raising device.—Between the shafts 72 and 78 I have provided a crank shaft 213, in which there are two cranks 214 and 215. Slidably mounted on the inner lower portions of the uprights 63 and 64 are two lifting bars 216 and 217, having the angular extensions 218 and 219 at their lower ends, projecting inwardly, designed to engage the under portions of the ends of the mold as the mold frames are brought in line with them.

Adjustably secured at one end to the lifting plate 216, and at its other end to the crank 214 is a pitman 220. Adjustably attached to the lifting plate 217 at one end and to the crank 215 at its other, is a pitman 221. These pitmen and lifting plates are so arranged that as the releasing plunger, hereinafter described, is held in engagement

with the material within the molds, and as the crank shaft 213 is operated, the mold frames will be raised until the spring pressed member 50 enters the notches 49 in the mold frame. The lifting plates are then moved to their lower limits of movement, where they are in readiness to receive the next mold frame advanced by the conveyer. The shaft 213, by which the mold raising device is operated, is driven through a gear 221^a mounted on it, and which is in mesh with the gear 81 on the shaft 78, which is driven through the gears 79 and 74, the shaft 72 and the bevel gears 73 and 71 from the main driving shaft 66 of the machine.

As has been before stated, the gear 81 is mutilated so that the lifting device is allowed to remain at rest at its lower limit of movement while the conveyer is being advanced a sufficient distance to bring the next mold frame to proper position for being lifted by this device, and while the pallet is being carried rearwardly to a point of delivery.

I have provided two guide plates 222 and 223 on the gears 81 and 221, respectively, arranged to keep the gears in line with each other while the mutilated portion of the gear 81 is nearest the gear 221.

The releasing plunger.—Secured to the uprights 63 and 64, and near their inner top portions are two guides 224 and 225, respectively, in which a vertically movable releasing plunger head 226 is mounted. Secured to the releasing plunger head 226 are two pitmen 227 and 228, which are connected at their upper ends with two rock arms 229 and 230, respectively. These rock arms are mounted on the shaft 231 which is rotatably mounted in the hangers 232 and 233, which are secured to and extend downwardly from the arch 65, as shown clearly in Fig. 16 of the drawings.

Mounted on the central portion of the shaft 231 is a pinion 234, in mesh with the rack 235. The rack 235 is secured to a sliding member 236, supported at one end by the block 237, mounted on the shaft 213 and at its other end, is supported by the blocks 238 on the shaft 78. There is a roller 239 secured to the sliding member 236 which enters the groove 240 of the cam 80, so that as the cam is driven by the shaft 78, the sliding member will be oscillated and cause the rack 235 to impart an alternate rotary motion to the pinion 234, and hence cause the releasing plunger to be raised and lowered as the driving shaft is operated.

Thus it will be seen by means of the above construction, when the mold is advanced by the conveyer to the proper position beneath the releasing plunger, this plunger, which is properly timed with all of the rest of the mechanism of the device, is moved down-

wardly until the retaining members 241 engage the formed article in each of the molds, and holds this article against the pallets and against upward movement as the mold frame is drawn upwardly. After the mold frame has been raised, the releasing plunger is drawn out of engagement with the articles formed, and the conveyer again advances to deliver the pallet board at the rear where it is removed from the conveyer and set away, together with the articles formed upon it, which have by this mechanism been retained in unbroken contact with the pallet to allow them to be set away and allowed to dry while they are thus in contact with the polished, smooth or nonadhesive surface of the pallet.

The brake.—Beneath the balance wheel, and between the upright 64 and the left upright 61 is a rock shaft 242, having a bell crank lever secured to its central portion, upon the inner arm of which the brake shoe 243 is mounted, and to the outer arm of which is pivotally attached a connecting rod 244, which connecting rod is pivotally attached at its lower end to a rock arm 245 secured to the rock shaft 246, and which shaft is rotatably mounted in suitable bearings on the left side of the main frame. Attached to the rock shaft 246 are a number of operating levers 247 which may be moved downwardly at their outer ends by the operator for throwing the brake shoe 243 against the fly wheel 70 and instantaneously stop the operation of the machinery. There is a spring 248 secured at its lower end to the main frame, and at its upper end to a rock arm 249, attached to the shaft 242 for throwing the brake shoe out of engagement with the fly wheel. Suitable water pipes 250, properly controlled by faucets and stop-cocks are provided which furnish the proper water supply for the mixing troughs 87 and 160.

Practical operation.—In the practical operation of the machine, and assuming that the driving belts have been thrown onto the driving pulleys 67 and 135, and that the surfacing materials are being properly supplied to the material storing and delivering hoppers 90 and 163, and that the aggregate hopper is receiving its material properly from the aggregate mixer 140, and that water is being fed into the mixing troughs 87 and 160 through the supply pipes 250, and that the parts of the mechanism are in gear, the entire mechanism is in readiness for operation. The pallets 48 are placed in position on the conveyer at the forward end of the machine beneath the mold frames as fast as each pallet bed plate and mold frame is advanced with the conveyer.

Following the progress of a single mold frame through the machine, it will be seen

that the mold frame first comes to position beneath the edge surfacing feeder which, through the mechanism heretofore described, allows the surfacing material, which preferably comprises a fine mixture of materials thoroughly mixed by this feeder to be delivered into the molds. This mold frame is then advanced to a position beneath the aggregate hopper, where the molds receive a supply of the coarser, but thoroughly mixed material which comprises the body of the article to be formed. When the mold frame is advanced rearwardly to a position beneath the facing spacer, the prongs of this spacer enter the rear ends of the molds and crowd the material toward the forward end of the mold and provide a space to receive the surfacing material which forms the end of the article from the end surfacing feeder. As the mold frame continues its progress, it is brought to a position immediately beneath the tamping plunger, whereupon the article within the molds is thoroughly tamped and crowded into a dense mass. The plunger is then drawn upwardly, the mold advanced rearwardly to a point where the releasing plunger holds the article in contact with the bottom of the molds, or pallet, and the mold elevating device raises the mold frame out of engagement with these articles, whereupon the releasing plunger is raised and the pallet is freed so that it may, together with the articles formed thereon, be removed from the rear of the machine without breaking the contact between the articles formed and the polished, smooth, or non-adhesive surface of the pallet which has, throughout the entire operation, formed the bottom of the molds. The pallet, together with the articles is then preferably set away to allow the articles to be dried and hardened. The mold frame is then carried by the conveyer, beneath the mold frames which are being filled, to a point of starting. During all of this operation, the various operative parts are so timed and regulated by the construction described, that certain of the operations are being performed simultaneously, while there is a pause in a certain other of the operations to allow for the proper filling of the molds, the proper spacing in the molds, the proper tamping of the materials, and the releasing of the articles, and for the delivering and supply of the pallets.

1. In a device of the class described, a frame, a conveyer operatively mounted in the frame, a series of pallet bed plates in the conveyer, a pair of posts having a screw threaded and tapered lower end entering a tapered and screw threaded opening in the bed plate, which tapered end and opening together maintain the posts in a vertical position, a mold frame loosely mounted between the posts on each bed plate, a pallet

mounted on the pallet bed plate to form the bottom of the mold, means for feeding materials into the mold frames, and means for operating the conveyer.

- 5 2. In a device of the class described, a frame, a conveyer operatively mounted in the frame, a series of pallet bed plates in the conveyer, a pair of posts having a screw threaded and tapered lower end entering a 10 tapered and screw threaded opening in the bed plate, which tapered end and opening together maintain the posts in a vertical position, a mold frame loosely mounted between the posts on each bed plate, a limiting 15 stop on each of the posts for limiting the outer movement of the mold frames, a pallet mounted on the pallet bed plate to form the bottom of the mold, means for feeding material into the mold frames, and means for 20 intermittently operating the conveyer.

3. In a device of the class described, a frame, a conveyer operatively mounted in the frame, a series of pallet bed plates in the conveyer, a pair of posts having a screw 25 threaded and tapered lower end entering a tapered and screw threaded opening in the bed plate, to maintain the posts rigidly in a vertical position, a mold frame loosely mounted between the posts on each bed 30 plate, a pallet mounted on the pallet bed plate to form the bottom of the mold, means for automatically feeding material into the mold frames, and means for operating the conveyer.

- 35 4. In a device of the class described, a conveyer, a series of mold frames having molds therein, in which articles are formed, a series of pallets mounted on the conveyer beneath the mold frames, designed to form 40 the bottoms of the molds while the article is being formed in them, means for automatically delivering material into the molds, means for holding the article formed within the molds in contact with the pallet while 45 the mold frame is being raised, and means for raising the mold frame so that the pallets, with the articles formed thereon, may be lifted from the conveyer at the rear of the machine.

50 5. In a device of the class described, a conveyer, a series of mold frames on the conveyer, a pallet having a polished and non-adhesive surface forming the bottom of each mold frame, and means for raising the 55 mold frame while the articles formed therein are held in contact with the pallet to allow the pallet to be removed with the articles thereon.

- 60 6. In a device of the class described, a conveyer, a series of mold frames on the conveyer, a pallet having a polished and non-adhesive surface forming the bottom of each mold frame, and automatic means for raising the mold frame while the articles formed

therein are held in unbroken contact with 65 the pallet, to allow the pallet to be removed with the articles thereon.

7. In a device of the class described, a conveyer, a series of mold frames on the conveyer, a pallet having a polished and non-adhesive surface forming the bottom of each mold frame, means for raising the mold frame while the articles formed therein are held in contact with the pallet to allow the 70 pallet to be removed with the articles thereon, and means for automatically delivering the materials into the mold frames which are to be formed into articles by the molds.

8. In a device of the class described, a conveyer, a series of mold frames on the conveyer, a pallet forming the bottom of each mold frame, automatic means for raising the mold frame while the articles formed therein are held in unbroken contact with the pallet, to allow the pallet to be removed 80 with the articles thereon, means for automatically delivering the materials into the mold frames which are formed into articles by the molds.

9. In a device of the class described, a 90 conveyer, a series of mold frames movable upward away from said conveyer and having molds in which the articles are designed to be formed, a series of pallets each having a polished or non-adhesive surface mounted 95 on the conveyer and forming a surface of the molds, while the articles are being formed in them, and means for automatically raising said mold frames upward away from the conveyer to release the pallets and 100 the articles formed on them without breaking the contact between the articles and the pallets.

10. In a device of the class described, a 105 conveyer, a series of mold frames mounted thereon and movable upward away from said conveyer, said frames having molds in which the articles are designed to be formed, a series of pallets each having a polished or 110 non-adhesive surface mounted on the conveyer and forming a surface of the molds, while the articles are being formed in them, and means for automatically raising said mold frames upward away from the conveyer to release the pallets and the articles 115 formed on them without breaking the contact between the articles and the pallets, to allow the pallets to be removed and set away with the articles in contact with them, so that they may dry and harden, and a 120 polished or smooth surface may be imparted to the articles similar to that upon the pallets.

11. In a device of the class described, a 125 conveyer, a series of mold frames mounted thereon and movable upward away from said conveyer, said frames having molds in which the articles are designed to be formed,

a series of pallets each having a polished or non-adhesive surface mounted on the conveyer and forming a surface of the molds, while the articles are being formed in them, 5 means for automatically raising said mold frames upward away from the conveyer to release the pallets and the articles formed on them without breaking the contact between the articles and the pallets, to allow 10 the pallets to be removed and set away with the articles in contact with them, so that they may dry and harden, and a polished or smooth surface may be imparted to the articles similar to that upon the pallets, and 15 means for automatically delivering material into the molds.

12. In a device of the class described, a conveyer, a series of mold frames mounted thereon and movable upward away from 20 said conveyer, said frames having molds in which the articles are designed to be formed, a series of pallets each having a polished or non-adhesive surface mounted on the conveyer and forming a surface of the molds, 25 while the articles are being formed in them, means for automatically raising said mold frames upward away from the conveyer to release the pallets and the articles formed on them without breaking the contact between 30 the articles and the pallets, to allow the pallets to be removed and set away with the articles in contact with them, so that they may be dry and harden, and a polished or smooth surface may be imparted to the 35 articles similar to that upon the pallets, and means for operating the conveyer intermittently.

13. In a device of the class described, a conveyer, a series of mold frames mounted 40 thereon and movable upward away from said conveyer, said frames having molds in which the articles are designed to be formed, a series of pallets each having a polished or non-adhesive surface mounted on the conveyer and forming a surface of the molds, 45 while the articles are being formed in them, and means for automatically raising said mold frames upward away from the conveyer to release the pallets and the articles formed on them without breaking the contact 50 between the articles and the pallets, to allow the pallets to be removed and set away with the articles in contact with them, so that they may dry and harden, and a polished or smooth surface may be imparted to the 55 articles similar to that upon the pallets, and means for operating the conveyer and the releasing mechanism intermittently.

14. In a device of the class described, a conveyer, a series of mold frames mounted 60 thereon and movable upward away from said conveyer, said frames having molds in which the articles are designed to be formed, 65 a series of pallets each having a polished or

non-adhesive surface mounted on the conveyer and forming a surface of the molds, while the articles are being formed in them, means for automatically raising said mold frames upward away from the conveyer to 70 release the pallets and the articles formed on them without breaking the contact between the articles and the pallets, to allow the pallets to be removed and set away with the articles in contact with them, so that 75 they may dry and harden, and a polished or smooth surface may be imparted to the articles similar to that upon the pallets, means for operating the conveyer intermittently, and means for operating the means for delivering materials into the molds.

15. In a device of the class described, a conveyer, a series of mold frames mounted thereon and movable upward away from said conveyer, said frames having molds in 85 which the articles are designed to be formed, a series of pallets each having a polished or non-adhesive surface mounted on the conveyer and forming a surface of the molds, while the articles are being formed in them, 90 means for automatically raising said mold frames upward away from the conveyer to release the pallets and the articles formed on them without breaking the contact between the articles and the pallets, to allow 95 the pallets to be removed and set away with the articles in contact with them, so that they may dry and harden, and a polished or smooth surface may be imparted to the articles similar to that upon the pallets, 100 means for operating the conveyer and the releasing mechanism intermittently, and means for operating the means for delivering

material into the molds.

16. In a device of the class described, a 105 conveyer, a series of mold frames having molds therein in which the articles are designed to be formed, a series of pallets each having a polished or non-adhesive surface mounted on the conveyer and forming a surface of the molds, while the articles are being formed in them, means for automatically releasing the pallets and the articles formed on them without breaking the contact between the articles and the pallets, to allow 110 the pallets to be removed and set away with the articles in contact with them so that they may dry and harden, and a smooth or polished surface may be imparted to the articles similar to that upon the pallets, means 115 for operating the conveyer and the releasing mechanism intermittently, and means for operating the means for delivering material into the molds, a brake for controlling the means which operates the conveyer and the 120 releasing mechanism.

17. In a device of the class described, an endless conveyer, a series of mold frames each movable upward away from the conveyer while the conveyer is in motion, a se- 125 130

- ries of pallets mounted on said conveyer and each having a polished non-adhesive surface which together with the mold frames form complete molds in which articles may be shaped, and means for raising said mold frames upward away from the conveyer to release the pallets carried by said conveyer.
18. In a device of the class described, an intermittently operated conveyer, mold frames mounted on the conveyer and capable of limited movement upward away from it, pallets having a polished or non-adhesive surface designed to be engaged by material fed into the mold frames for imparting a finish to the article which comes in contact with said surface, and means for feeding materials into the mold frames.
19. In a device of the class described, an intermittently operated chain conveyer, mold frames mounted on the conveyer and capable of limited movement upward away from it, pallets mounted above said conveyer and having a polished or non-adhesive surface designed to be engaged by material fed into the mold frames for imparting a finish to the article which comes in contact with said surface, means for feeding materials into the mold frames, means for thoroughly mixing the materials before they are fed into the mold frames and means for lifting the mold frames away from the chain conveyer when the molded articles are to be removed.
20. In a device of the class described, an intermittently operated conveyer, mold frames mounted on the conveyer and capable of limited movement away from it, pallets having a polished or non-adhesive surface designed to be engaged by material fed into the mold frames for imparting a finish to the article which comes in contact with said surface, and means for feeding materials into the mold frames, means for mixing the material, a water supply leading to the means for mixing the materials.
21. In a device of the class described, an intermittently operated conveyer, mold frames mounted on the conveyer and capable of limited movement away from it, pallets having a polished or non-adhesive surface designed to be engaged by material fed into the mold frames for imparting a finish to the article which comes in contact with said surface, means for feeding materials into the mold frames, and means for maintaining the mold frames some distance away from the conveyer at the forward end of the machine to allow the pallets to be inserted on the conveyer and beneath said mold frames.
22. In a device of the class described, an intermittently operated conveyer, mold frames mounted on the conveyer and capable of limited movement away from it, pallets having a polished or non-adhesive surface designed to be engaged by material fed
- into the mold frames for imparting a finish to the article which comes in contact with said surface, means for feeding materials into the mold frames, means for thoroughly mixing the materials before they are fed into the mold frames, and means for maintaining the mold frames some distance away from the conveyer at the forward end of the machine to allow the pallets to be inserted on the conveyer and beneath the said mold frames.
23. In a device of the class described, an intermittently operated conveyer, mold frames mounted on the conveyer and capable of limited movement away from it, pallets having a polished or non-adhesive surface designed to be engaged by material fed into the mold frames for imparting a finish to the articles which come in contact with said surface, means for feeding materials into the mold frames, a water supply leading to the means for mixing the materials, and means for maintaining the mold frames some distance away from the conveyer at the forward end of the machine to allow the pallets to be inserted on the conveyer and beneath said mold frames.
24. In a device of the class described, an intermittently operated conveyer, mold frames mounted on the conveyer and capable of limited movement away from it, pallets having a polished or non-adhesive surface designed to be engaged by material fed into the mold frames for imparting a finish to the article which comes in contact with said surface, means for feeding materials into the mold frames, and a releasing mechanism for raising the mold frames, and allowing the pallets with the material which had been formed with the mold frames to be removed simultaneously and without breaking the contact between the pallets and the articles formed upon them.
25. In a device of the class described, an intermittently operated conveyer, mold frames mounted on the conveyer and capable of limited movement away from it, pallets having a polished or non-adhesive surface designed to be engaged by material fed into the mold frames for imparting a finish to the article which comes in contact with said surface, means for feeding material into the mold frames, a releasing mechanism for raising the mold frames and allowing the pallets with the material which had been formed with the mold frames to be removed simultaneously and without breaking the contact between the pallets and the articles formed upon them.
26. In a device of the class described, an intermittently operated conveyer, mold frames mounted on the conveyer and capable of limited movement away from it, pallets having a polished or non-adhesive surface designed to be engaged by material fed

into the mold frames for imparting a finish to the article which comes in contact with said surface, means for feeding materials into the mold frames, means for thoroughly 5 mixing the materials before they are fed into the mold frames, and a releasing mechanism for raising the mold frames and allowing the pallets with the material which had been formed with the mold frames to be simultaneously removed, and without breaking the contact between the pallets and the articles formed upon them.

27. In a device of the class described, an intermittently operated conveyer, mold 15 frames mounted on the conveyer and capable of limited movement away from it, pallets having a polished or non-adhesive surface designed to be engaged by material fed into the mold frames for imparting a 20 finish to the article which comes in contact with said surface, means for feeding materials into the mold frames, a water supply leading to the means for mixing the materials, and a releasing mechanism for allowing the pallets with the material which has been formed with the mold frames to be removed simultaneously and without breaking the contact between the pallets and the articles formed upon them.

30. 28. In a device of the class described, an intermittently operated conveyer, mold frame mounted on the conveyer and capable of limited movement away from it, pallets having a polished or non-adhesive surface 35 designed to be engaged by material fed into the mold frames for imparting a finish to the article which comes in contact with said surface, means for feeding materials into the mold frames, means for maintaining 40 the mold frames some distance away from the conveyer at the forward end of the machine to allow the pallets to be inserted on the conveyer and beneath said mold frames, and a releasing mechanism for raising the 45 mold frames and allowing the pallets with the material which had been formed with the mold frames to be removed simultaneously and without breaking the contact between the pallets and the articles formed 50 upon them.

29. In a device of the class described, an intermittently operated conveyer, mold frames mounted on the conveyer and capable of limited movement away from it, pallets having a polished or non-adhesive surface 55 designed to be engaged by material fed into the mold frames for imparting a finish to the articles which come in contact with said surface, means for feeding materials 60 into the mold frames, means for thoroughly mixing the materials before they are fed into the mold frames, means for maintaining the mold frames some distance away from the conveyer at the forward end of the machine to allow the pallets to be in-

serted on the conveyer and beneath the said mold frames, and a releasing mechanism for raising the mold frames and allowing the pallets with the material which had been formed with the mold frames to be removed simultaneously and without breaking the contact between the pallets and the articles formed upon them. 70

30. In a device of the class described, an intermittently operated conveyer, mold 75 frames mounted on the conveyer and capable of limited movement away from it, pallets having a polished or non-adhesive surface designed to be engaged by material fed into the mold frames for imparting a 80 finish to the articles which come in contact with said surface, means for feeding materials into the mold frames, a water supply leading to the means for mixing the materials, means for maintaining the mold 85 frames some distance away from the conveyer at the forward end of the machine to allow the pallets to be inserted on the conveyer and beneath said mold frames, and a releasing mechanism for raising the 90 mold frames and allowing the pallets with the material which had been formed with the mold frames to be removed simultaneously and without breaking the contact 95 between the pallets and the articles formed upon them.

31. In a device of the class described, a frame, a conveyer mounted in the frame, mold frames on the conveyer having molds therein, pallets for the molds, a surfacing 100 feeder designed to supply thoroughly mixed material into the bottom of the molds, an aggregate hopper for supplying thoroughly mixed material into the molds on top of the material supplied by the surfacing feeder, 105 a tamping plunger, a driving mechanism operatively connected with the conveyer and the tamping plunger for operating them, a releasing plunger designed to hold the articles formed within the molds in contact 110 with the pallets, while the mold frame is being raised, and a releasing mechanism for raising the mold frame.

32. In a device of the class described, a frame, a conveyer mounted in the frame, mold frames on the conveyer having molds therein, pallets for the molds, a surfacing 115 feeder designed to supply thoroughly mixed material into the bottom of the molds, an aggregate hopper for supplying thoroughly 120 mixed material into the molds on top of the material supplied by the surfacing feeder, a releasing plunger designed to hold the articles formed within the molds in contact with the pallets while the mold frame is 125 being raised, and a releasing mechanism for raising the mold frame.

33. In a device of the class described, a frame, a conveyer mounted in the frame, mold frames movably secured to the con- 130

veyer having molds therein, detachable pallets forming a portion of the molds, a surfacing feeder for delivering fine material into the molds, an aggregate hopper 5 through which a coarser material is delivered into the mold, a tamping plunger for crowding the material within the molds into a dense mass, and means for automatically releasing the articles formed within the 10 molds, together with the pallets, from the mold frames, for the purpose set forth.

34. In a device of the class described, a frame, a conveyer mounted in the frame, mold frames movably secured to the conveyer having molds therein, detachable pallets forming a portion of the molds, a surfacing feeder for delivering fine material into the molds, means for regulating the feeding of the material from the surfacing 15 feeder, an aggregate hopper through which a coarser material is delivered into the mold, a tamping plunger for crowding the material within the molds into a dense mass, and means for automatically releasing the 20 articles formed within the molds, together with the pallets, from the mold frames for the purpose set forth.

35. In a device of the class described, a frame, a conveyer mounted in the frame, mold frames movably secured to the conveyer having molds therein, detachable pallets forming a portion of the molds, a surfacing feeder for delivering fine material into the molds, means for regulating the feeding of the material from the surfacing 30 feeder, adjustable means for regulating the supply of the various materials to be mixed in the surfacing feeder, an aggregate hopper through which a coarser material is delivered into the mold, a tamping plunger for crowding the material within the molds into a dense mass, and means for automatically releasing the articles formed within the 35 molds, together with the pallets from the mold frames for the purpose set forth.

36. In a device of the class described, a conveyer, mold frames on the conveyer having molds therein, an edge surfacing feeder designed to suitably mix surfacing material 40 with water and deliver the same thoroughly mixed into the molds automatically, an aggregate hopper designed to deliver thoroughly mixed coarser material on top of the edge surfacing material, a facing 45 spacer designed for entering each mold near one end thereof, and forcing the material toward the other end of each mold, an end surfacing feeder for delivering thoroughly mixed material into the opening formed by 50 the facing spacer, and a tamping plunger for crowding the material which has thus been fed into the molds, into a dense mass within the molds.

37. In a device of the class described, a 55 conveyer, mold frames on the conveyer hav-

ing molds therein, an edge surfacing feeder designed to suitably mix surfacing material with water and deliver the same thoroughly mixed into the molds automatically, an aggregate hopper designed to deliver thoroughly mixed coarser material on top of the edge surfacing material, a facing spacer designed for entering each mold near one end thereof, and forcing the material toward the other end of each mold, an end 70 surfacing feeder for delivering thoroughly mixed material into the opening formed by the facing spacer, a tamping plunger for crowding the material which has thus been fed into the molds into a dense mass within 75 the molds, and a releasing plunger for holding the formed articles in position while the mold frames are raised to enable the articles to be removed.

38. In a device of the class described, a 80 conveyer, mold frames on the conveyer having molds therein, an edge surfacing feeder designed to suitably mix surfacing material with water and deliver the same thoroughly mixed into the molds automatically, an aggregate hopper designed to deliver thoroughly mixed coarser material on top of the edge surfacing material, a facing spacer designed for entering each mold near one end thereof, and forcing the material 85 toward the other end of each mold, an end surfacing feeder for delivering thoroughly mixed material into the opening formed by the facing spacer, a tamping plunger for crowding the material which has thus been 90 fed into the molds into a dense mass within the molds, a releasing plunger for holding the formed articles in position while the mold frames are raised to enable the articles to be removed, and a rear mold supporting 95 bracket for maintaining the mold frames at their outer limits of movement from the conveyer, during the delivery of the articles.

39. In a device of the class described, a 100 conveyer, mold frames on the conveyer having molds therein, an edge surfacing feeder designed to suitably mix surfacing material with water and deliver the same thoroughly mixed into the molds automatically, an aggregate hopper designed to deliver thoroughly mixed coarser material on top of the edge surfacing material, a facing spacer designed for entering the mold near one end thereof and forcing the material toward the other end of each mold, an end 105 surfacing feeder for delivering thoroughly mixed material into the opening formed by the facing spacer, a tamping plunger for crowding the material which has thus been fed into the molds into a dense mass within 110 the molds, a releasing plunger for holding the formed articles in position while the mold frames are raised to enable the articles to be removed, a rear mold supporting 115 bracket for maintaining the mold frames at 120 their outer limits of movement from the conveyer, during the delivery of the articles.

40. In a device of the class described, a 125 conveyer, mold frames on the conveyer having molds therein, an edge surfacing feeder designed to suitably mix surfacing material with water and deliver the same thoroughly mixed into the molds automatically, an aggregate hopper designed to deliver thoroughly mixed coarser material on top of the edge surfacing material, a facing spacer designed for entering each mold near one end thereof, and forcing the material toward the other end of each mold, an end surfacing feeder for delivering thoroughly mixed material into the opening formed by the facing spacer, a tamping plunger for crowding the material which has thus been fed into the molds into a dense mass within the molds, a releasing plunger for holding the formed articles in position while the mold frames are raised to enable the articles to be removed, a rear mold supporting 130 bracket for maintaining the mold frames at

their outer limits of movement from the conveyer, during the delivery of the articles, and a front mold supporting bracket for maintaining the molds at their outer limits of movement away from the conveyer while the pallets which form the bottom of the molds are being placed upon the conveyer.

40. In a device of the class described, a series of connected molds and means to advance the same, a surfacing feeder comprising material feeding wheels, a mixing trough into which material is delivered by the material feeding wheels, mixing blades operatively mounted in the mixing trough, a grooved feeding shaft, the grooves in which are designed to receive mixing material when at their upper limits of movement, and deliver material when at their lower limits of movement, and a feeding plate for delivering the material into molds or other forming mechanisms beneath.

41. In a device of the class described, a series of connected molds and means to advance the same, a surfacing feeder comprising material feeding wheels, means for regulating the speed of each of the material feeding wheels relative to each other, a mixing trough into which material is delivered by the material feeding wheels, mixing blades operatively mounted in the mixing trough, a grooved feeding shaft, the grooves in which are designed to receive mixing material when at their upper limits of movement, and deliver material when at their lower limits of movement, and a feeding plate for delivering the material into molds or other forming mechanisms beneath.

42. In a device of the class described, a series of connected molds and means to advance the same, a surfacing feeder comprising material feeding wheels, means for regulating the speed of the material feeding wheels relative to each other, a mixing trough, mixing blades in the mixing trough, water supply pipes leading into the mixing trough, a grooved feeding shaft having its grooves of such size as to receive from the mixing trough the proper quantity of mixed materials, and deliver the same therefrom, and means for delivering materials from the mixing trough after they have been thoroughly mixed into molds or other forming mechanisms.

43. In a device of the class described, a series of molds and means for advancing the same, a surfacing feeder comprising material feeding wheels, means for regulating the speed of the material feeding wheels relative to each other, a mixing trough, mixing blades in the mixing trough, water supply pipes leading into the mixing trough, a grooved feeding shaft having its grooves of such size as to receive from the mixing trough the proper quantity of mixed materials and deliver the same therefrom, means

for delivering materials from the mixing trough after they have been thoroughly mixed, into molds or other forming mechanisms, and adjustable means for regulating the speed of the grooved feeding shaft.

44. In a device of the class described, a surfacing feeder comprising material feeding wheels, means for regulating the speed of the material feeding wheels relative to each other, a mixing trough, mixing blades in the mixing trough water supply pipes leading into the mixing trough, a grooved feeding shaft having its grooves of such size as to receive from the mixing trough the proper quantity of mixed materials, and deliver the same therefrom, means for delivering materials from the mixing trough after they have been thoroughly mixed, into molds or other forming mechanisms, a feeding plate for receiving the materials from the grooved feeding shaft, and means for automatically operating the feeding plate for delivering the materials fed upon it by the grooved feeding shaft into molds or other forming mechanisms.

45. In a device of the class described, a surfacing feeder comprising material feeding wheels, means for regulating the speed of the material feeding wheels relative to each other, a mixing trough, mixing blades in the mixing trough, water supply pipes leading into the mixing trough, a grooved feeding shaft having its grooves of such size as to receive from the mixing trough the proper quantity of mixed materials and deliver the same therefrom, means for delivering materials from the mixing trough after they have been thoroughly mixed, into molds or other forming mechanism, adjustable means for regulating the speed of the grooved feeding shaft, a feeding plate for receiving the materials from the grooved feeding shaft, and means for automatically operating the feeding plate for delivering the materials fed upon it by the grooved feeding shaft, into molds or other forming mechanisms.

46. In a device of the class described, a surfacing feeder comprising material feeding wheels, a mixing trough into which material is delivered by the material feeding wheels, mixing blades operatively mounted in the mixing trough, a grooved feeding shaft, the groves in which are designed to receive mixed material when at their upper limits of movement, and deliver material at their lower limits of movement, a feeding plate for delivering the materials, means for receiving materials from the feeding plate, and a conveyer upon which said molds are mounted, for delivering the materials formed in the molds.

47. In a device of the class described, a surfacing feeder comprising material feeding wheels, a mixing trough into which ma-

terial is delivered by the material feeding wheels, mixing blades operatively mounted in the mixing trough, a grooved feeding shaft, the grooves in which are designed 5 to receive mixed material when at their upper limits of movement, and deliver material when at their lower limits of movement, a feeding plate for delivering the materials, means for receiving materials 10 from the feeding plate, a conveyer upon which said molds are mounted for delivering the materials formed in the molds, and a tamping plunger for crowding material within the molds into a dense mass while 15 these molds are upon the conveyer.

48. In a device of the class described, a surfacing feeder comprising material feeding wheels, a mixing trough into which material is delivered by the material feeding 20 wheels, mixing blades operatively mounted in the mixing trough, a grooved feeding shaft, the grooves in which are designed to receive mixed material when at their upper limits of movement and deliver material 25 when at their lower limits of movement, a feeding plate for delivering the materials, means for receiving materials from the feeding plate, a conveyer upon which said molds are mounted for delivering the materials 30 formed in the molds, a tamping plunger for crowding material within the molds into a dense mass while these molds are upon the conveyer, and a releasing mechanism for releasing the articles formed from the molds. 35

49. In a device of the class described, a series of mold frames having molds therein, and pallets for forming the bottoms of the molds detachably connected with the mold 40 frames, a conveyer, means for driving the conveyer forwardly at intermittent periods, and means for automatically releasing the articles formed in the molds, together with the pallets by raising the mold frames while the articles are held in unbroken contact 45 with the pallets.

50. In a device of the class described, a series of mold frames having molds therein, and pallets for forming the bottoms of the molds detachably connected with the mold 50 frames, a conveyer, means for driving the conveyer forwardly at intermittent periods, means for automatically releasing the articles formed in the molds, together with the pallets, by raising the mold frames while 55 the articles are held in unbroken contact with the pallets, and means for automatically feeding properly mixed material into the molds.

51. In a device of the class described, a series of mold frames having molds therein, and pallets for forming the bottoms of the molds detachably connected with the mold 60 frames, a conveyer, means for driving the conveyer forwardly at intermittent periods, means for automatically releasing the arti- 65

cles formed in the molds, together with the pallets, by raising the mold frames while the articles are held in unbroken contact with the pallets, means for automatically feeding properly mixed material into the 70 molds, and a tamping plunger for crowding materials thus fed into the molds, into a compact and dense mass.

52. In a device of the class described, a mold frame having a series of molds therein, 75 pallets forming the bottoms of the molds, a releasing mechanism comprising a releasing plunger designed to engage the articles within the molds, a mold raising device for raising the mold frame while the releasing plunger holds the articles in unbroken contact with the pallets, and these articles in the pallets at their lower limits of movement, and a spring pressed plate for retaining the mold frames at their upper limits of movement as soon as they are drawn in line with these plates by the mold raising device. 80

53. In a device of the class described, a mold frame having a series of molds therein, 85 pallets forming the bottoms of the molds, a releasing mechanism comprising a releasing plunger designed to engage the articles within the molds, a mold raising device for raising the mold frame while the releasing plunger holds the articles in unbroken contact with the pallets, and these articles in the pallets at their lower limits of movement, a spring pressed plate for retaining the mold frames at their upper limits of 90 movement as soon as they are drawn in line with these plates by the mold raising device, and a conveyer upon which the pallets are detachably mounted, and upon which the mold frames are movably mounted. 95

54. In a device of the class described, a 100 mold frame having a series of molds therein, pallets forming the bottoms of the molds, a releasing mechanism comprising a releasing plunger designed to engage the articles within the molds, a mold raising device for 105 raising the mold frame while the releasing plunger holds the articles in unbroken contact with the pallets, and these articles in the pallets at their lower limits of movement, a spring pressed plate for retaining the mold frames at their upper limits of movement as soon as they are drawn in line with these plates by the mold raising device, and a material feeding device for automatically supplying properly mixed material in proper 110 quantities into the molds. 115

55. In a device of the class described, a mold frame having a series of molds therein, 120 pallets forming the bottoms of the molds, a releasing mechanism comprising a releasing plunger designed to engage the articles within the molds, a mold raising device for raising the mold frame while the releasing plunger holds the articles in unbroken contact 125 with the pallets, and these articles in the 130

pallets at their lower limits of movement, a material feeding device for automatically supplying properly mixed material in proper quantities into the molds, and a tamping plunger designed to crowd the material fed into the molds, into a dense mass, while within the molds.

56. In a device of the class described, a mold frame having a series of molds therein, pallets forming the bottoms of the molds, a releasing mechanism comprising a releasing plunger designed to engage the articles within the molds, a mold raising device for raising the mold frame while the releasing plunger holds the articles in unbroken contact with the pallets, and these articles in the pallets at their lower limits of movement, a spring pressed plate for retaining the mold frames at their upper limits of movement as soon as they are drawn in line with these plates by the mold raising device, a material feeding device for automatically supplying properly mixed material in proper quantities into the molds, and a tamping plunger designed to crowd the material fed into the molds into a dense mass while within the molds.

57. In a device of the class described, a mold frame having a series of molds therein, pallets forming the bottoms of the molds, a releasing mechanism comprising a releasing plunger designed to engage the articles within the molds, a mold raising device for raising the mold frame while the releasing plunger holds the articles in unbroken contact with the pallets, and these articles in the pallets at their lower limits of movement, a spring pressed plate for retaining the mold frames at their upper limits of movement as soon as they are drawn in line with these plates by the mold raising device, a conveyer upon which the pallets are detachably mounted, and upon which the mold frames are movably mounted, a material feeding device for automatically supplying properly mixed material in proper quantities into the molds, and a tamping plunger designed to crowd the material fed into the molds into a dense mass while within the molds.

58. In a device of the class described, a mold frame having a series of molds therein, a pallet having a polished or non-adhesive surface detachably connected with the mold frame and designed to form a portion of the forming surface of the mold, means for holding the articles formed in the mold in contact with the polished surface of the pallet, means for raising the mold frames for automatically releasing the pallets and the articles formed thereon, and a conveyer upon which the mold frame is mounted and above which it is lifted when the pallets and their articles are released.

59. In a device of the class described, a mold frame having a series of molds therein,

a pallet having a polished or non-adhesive surface detachably connected with the mold frame and designed to form a portion of the forming surface of the mold, means for holding the articles formed in the mold in contact with the polished surface of the pallet, means for raising the mold frames for automatically releasing the pallets and the articles formed thereon, and an intermittently driven conveyer upon which the mold frame is movably mounted, and upon which the pallet is mounted beneath the mold frame.

60. In a device of the class described, a mold frame having a series of molds therein, a pallet having a polished or non-adhesive surface detachably connected with the mold frame and designed to form a portion of the forming surface of the mold, means for holding the articles formed in the mold in contact with the polished surface of the pallet, means for raising the mold frames for automatically releasing the pallets and the articles formed thereon, and an intermittently driven conveyer upon which the mold frame is movably mounted, and upon which the pallet is mounted beneath the mold frame, and means for regulating the intermittent driving of the conveyer.

61. In a device of the class described, a mold frame having a series of molds therein, a pallet having a polished or non-adhesive surface detachably connected with the mold frame and designed to form a portion of the forming surface of the mold, means for holding the articles formed in the mold in contact with the polished surface of the pallet, means for raising the mold frames for automatically releasing the pallets and the articles formed thereon, and a conveyer upon which the mold frame is mounted, and means for detachably securing the pallets in position on the conveyer beneath the mold frames.

62. In a device of the class described, a conveyer, a series of mold frames having molds therein mounted upon the conveyer, a series of pallets mounted on the conveyer within the molds and designed to form the bottoms of the molds, and means for automatically releasing the molds from the articles formed by the molds, and the pallets, so that the pallets and articles may be discharged from the device in unbroken contact, and means for holding the pallets and the articles thereon in unbroken contact while being discharged from the device.

63. In a device of the class described, an endless conveyer, a series of mold frames thereon, each having a mold, pallets forming the bottoms of the molds, a plunger designed to engage the article within the mold and hold it in unbroken contact with the pallet, and a mold raising device for raising the mold frame during the time that the plunger is in position for holding the articles

in unbroken contact with their pallets, and means for supporting the molds in elevated positions away from the pallets and the articles thereon.

- 5 64. In a device of the class described, an endless conveyer, a series of mold frames thereon, each having a mold, pallets forming the bottoms of the molds, a plunger designed to engage the article within the mold and hold it in unbroken contact with the pallet, and a mold raising device for raising the mold frame during the time that the

plunger is in position for holding the articles in unbroken contact with their pallets, and a spring pressed plate for retaining the 15 mold frames at their upper limits of movement, after they have been elevated by the mold raising device.

Des Moines, Iowa, July 13, 1907.
